UNITED STATES PATENT OFFICE.

ADAM H. PRENZEL, OF HALIFAX, PENNSYLVANIA, ASSIGNOR TO UNITED SHOE MACHINERY COMPANY, OF PATERSON, NEW JERSEY, A CORPORATION OF NEW JERSEY.

METHOD OF MAKING SHOES.

1,131,732.

Specification of Letters Patent. Patented Mar. 16, 1915.

Application filed June 14, 1913. Serial No. 773,753.

To all whom it may concern:

Be it known that I, ADAM H. PRENZEL, a citizen of the United States, residing at Halifax, in the county of Dauphin and State of Pennsylvania, have invented certain new and useful Improvements in Methods of Making Shoes, of which the following is a specification, reference being had therein to the accompanying drawing.

10 This invention relates to improvements in the method of making shoes and is embodied in the steps presently to be described and claimed.

15 The object of the invention is that of simplifying the method of making shoes, cheapening the construction of the shoe, while preserving its strength and durability, and avoiding the necessity of turning the shoe or parts thereof or of providing what 20 is now commonly known as a welt shoe.

25 The method comprises generally the lasting of a lining to an inner sole, the lasting of an upper to the lining and inner sole, and application to the lining, upper and inner sole of the outer sole.

In the accompanying drawing is shown the various steps for the completion of the seam or shoe wherein,

30 Figure 1 shows a section through the last, the inner sole, and the lining, Fig. 2 is a similar view showing the application of the upper, while Fig. 3 shows the finished article.

35 In practising the process, an innersole B is temporarily secured to the bottom face of a last A. This inner sole is provided with a flexible edge part C of a width to extend beyond the edge of the inner sole and occupying a position on the bottom of the 40 inner sole. In building up the shoe, the inner sole is placed against the last with the tapes or flexible parts thereof presented outwardly.

45 The lining E is then drawn tight around the last and its edges are attached by a line of stitches e to the flexible part of the inner sole and below and inwardly beyond the edges of the inner sole. This forms a firm connection between the inner sole and the lining and results in the stretching and 50 proper positioning of the lining on the last.

55 The upper F is then stretched over the last and lining, drawn down below the edge of the inner sole, and is connected by a line of stitches f' to the lining, and the flexible part of the inner sole at a point close or adjacent

to the other line of stitches. In this condition, the outer sole C' is applied, the same being placed against the inner sole while the outer edges of the flexible part, lining and upper are bent upwardly horizontally, 60 the lining and the flexible part underlying the edge of the upper. Conveniently a welt G is then applied and the four members are next united by a line or lines of stitches g. In the finished article produced by the 65 method, it will be observed that the union between the lining, inner sole and upper are such as to maintain the upper in its proper condition and position directly under the edge of the inner sole, while the edges of 70 the upper are strengthened or reinforced by the underlying flexible parts of the lining and inner sole.

It will be observed that the method above described represents a series of steps which 75 can be performed by machines or means without the necessity of turning the shoe or parts thereof, and that the union between the parts is very strong. The finished article is one that has the appearance of an 80 ordinary shoe, while the expense of production is from a comparison much less than that of the ordinary methods heretofore employed.

The novel shoe produced by the process 85 herein described is made the subject matter of a copending application, Serial No. 773,752, of even date herewith. The broad process which involves the securing of the lining of the shoe to a lip or welt along the 90 edge of the innersole is described and claimed in my copending application Serial No. 768,973, filed May 21, 1913.

Having thus described the invention, what is claimed as new and desired to be 95 secured by Letters Patent is:

1. The method of making shoes consisting in supplying an inner sole with a flexible part at its edges on its outer face, lasting a lining to the inner sole and securing the 100 edges of the lining to the flexible part thereof, placing an upper over the lining, securing the edges of the upper to the flexible part and to the lining edge, projecting the edges of the upper, lining and flexible part 105 outwardly, applying an outer sole and uniting the edges of the upper, lining, flexible part, and outer sole, substantially as described.

2. The art of making shoes consisting in 110

providing an inner sole with a flexible attaching part on its under face adjacent to its edges, lasting a lining to the said flexible part below the edge of the inner sole by a line of stitches, placing an upper on the lining and securing the edges of the upper to the lining and to the flexible part below the edge of the inner sole, projecting the edge of the upper outwardly, placing an outer sole in position, placing a welt on the edge of the upper, and uniting the welt, upper and outer sole.

3. The art of making shoes consisting in

providing an inner sole with a flexible edge portion, uniting the edge of a lining to said flexible edge portion, uniting the edge of an upper to the lining and to the flexible portion, and connecting the upper, lining and flexible edge portion to the edge of the outer sole.

20

In testimony whereof I affix my signature in presence of two witnesses.

ADAM H. PRENZEL.
